(57) **CLAIM**

The ornamental design for a convertible cigarette extinguisher, as shown.

DESCRIPTION

FIG. 1 is a perspective view of a convertible cigarette extinguisher, showing my new design;

FIG. 2 is a side elevational view of a convertible cigarette extinguisher, showing my new design, the opposite side being a mirror image thereof;

FIG. 3 is a rear elevational view thereof;

FIG. 4 is a top plan view thereof;

FIG. 5 is a bottom view thereof;

FIG. 6 is a front elevational view thereof;

FIG. 7 is a side elevational view of the convertible cigarette extinguisher with the handle removed, the opposite side being a mirror image thereof;

FIG. 8 is a rear elevational view thereof;

FIG. 9 is a front elevational view thereof;

FIG. 10 is a top plan view thereof; and,

FIG. 11 is a bottom view thereof.
